CRISSCROSS BACK STRAP FOR SLIPS
AND THE LIKE

Max Schwartz, New York, N. Y.

Application November 24, 1945, Serial No. 630,603

5 Claims. (Cl. 2—73)

1

This invention relates to new and useful improvements in a criss-cross back strap for slips and the like.

More particularly, the invention proposes a new and improved back strap for slips, and the like garments, which have brassière-like sections which are open at the back. It is proposed to so arrange the criss-cross straps of each garment, that they are attached to the front of the brassière-like section and extend over the shoulders and across at the back. The back ends of the straps are attached to the top corners of the open back of the brassière-like section.

With the new arrangement, the brassière-like section can not readily slip off of the shoulders. The criss-cross arrangement of the back straps tends to tighten the front of the brassière-like section. The arrangement does not bind the wearer when bending or moving around.

Still further the invention proposes that the straps be adjustable for the convenience of the wearer.

It is contemplated to have the bottom end of the open back of the brassière-like section overlapped and sewed together to form a reinforced strengthened area.

The invention also contemplates a modified form in which the open back of the brassière is adjustable to various widths so as to better suit designs and types of outer garments.

Still further the invention proposes a new and improved back strap for slips and the like garments, as briefly explained, which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a front view of a slip provided with criss-cross back straps constructed in accordance with this invention.

Fig. 2 is a rear view of the slip shown in Fig. 1.

Fig. 3 is a fragmentary enlarged vertical sectional view taken on the line 3—3 of Fig. 2.

Fig. 4 is a fragmentary rear elevational view similar to Fig. 2 but illustrating the parts in a different position.

Fig. 5 is another fragmentary rear elevational view similar to Fig. 2, but illustrating the parts in still another position.

2

Fig. 6 is still another fragmentary rear elevational view of a slip which embodies a modified form of this invention.

Fig. 7 is a fragmentary enlarged detailed view of a portion of Fig. 6.

Fig. 8 is a fragmentary sectional view taken on the line 8—8 of Fig. 7.

The new and improved criss-cross back straps for slips and the like garments, in accordance with this invention, is used in combination with a slip 10 or the like garment, having a brassière-like section 11 which is open at the back, see Figs. 2 and 5. It is proposed that the open back of the brassière-like section be arranged so that the bottom portions of the yoke-like sides, forming the rear opening, overlap at the area 12 forming a triangularly shaped reinforced section. This section is secured closed with lines of stitches 14. Above this triangularly reinforced section, the sides of the open back are free to be bent to various positions, and for example, see Figs. 2, 4, and 5. In Fig. 4, the open back is substantially in a fully closed position. In Fig. 2, it is slightly open, and in Fig. 5, it is open to a greater degree.

Shoulder straps 16 are attached at their front ends 17 to the front of said brassière-like section 11. These shoulder straps 16 are intended to extend over the shoulders. At the back, the shoulder straps 16 cross. Their back ends are attached to the top corners 18 of the open back of the brassière-like section 11. Each of the straps 16 is provided with buckles 19, or other arrangements, by which the lengths of the shoulder straps 16 may be varied.

An important feature of the invention resides in the fact that because the shoulder straps 16 cross in the back, they are readily prevented from slipping off of the shoulders. When it is desired, it is possible to slip the shoulder straps off of the shoulders, and at the same time, it is possible to open the open back of the brassière-like section to various distances; as for example, see Figs. 4 and 5, so as to facilitate removing the garment.

Another feature resides in the fact that because the shoulder straps 16 cross at the back, they tend to tighten the front of the brassière-like section. It should be noticed that the shoulder straps are not binding, and will permit the wearer to bend in all directions.

In Figs. 6 to 8 inclusive, a modified form of the invention has been disclosed which is very similar to the prior form, distinguishing in the fact that a horizontal back strap 22 is associated with the shoulder straps 16 for limiting the pos-

sible extent to which the open back of the brassière-like section may open. More specifically, the back strap 22 has loop portions 23, on its ends, through which the shoulder straps 16 pass. A plurality of snap fasteners 24 are mounted along the length of the shoulder straps 16, in the vicinity of the back, of the garment. These snap fasteners 24 cooperate with complementary snap fasteners 25 which are mounted on and within the loops 23.

In other respects this form of the invention is similar to that previously shown and like reference numerals identify like parts in each of the several views.

The advantages and operation of this form of the invention are substantially identical to the prior form. It differs, however, in the fact that the back strap 22 may be placed in various elevated positions, along lengths of the crossed back portions of the shoulder straps 16. The back strap 22 will serve to limit the extent to which each of the backs of brassière-like sections may be opened.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In combination with a slip or the like garment having a brassière-like section which is open at the back, straps attached to the front of said brassière-like section for extending over the shoulders and crossing at the back and having their back ends attached to and tangential to the top corners of the open back of said brassière-like section, and a horizontal back strap having end loops through which the back portions of said straps pass.

2. In combination with a slip or the like garment, having a brassière-like section which is open at the back, straps attached to the front of said brassière-like section for extending over the shoulders and crossing at the back and having their back ends attached to the top corners of the open back of said brassière-like section, a horizontal back strap having end loops through which the back portions of said straps pass, and means for securing said back strap in various positions on the back portions of said straps.

3. In combination with a slip or the like garment, having a brassière-like section which is open at the back, straps attached to the front of said brassière-like section for extending over the

shoulders and crossing at the back and having their back ends attached to the top corners of the open back of said brassière-like section, a horizontal back strap having end loops through which the back portions of said straps pass, and means for securing said back strap in various positions on the back portions of said straps, comprising fastening elements along the lengths of said first named straps at the back and cooperative with complementary fastening elements upon said horizontal back strap.

4. In combination with a slip or the like garment, having a brassière-like section which is open at the back, straps attached to the front of said brassière-like section for extending over the shoulders and crossing at the back and having their back ends attached to the top corners of the open back of said brassière-like section, a horizontal back strap having end loops through which the back portions of said straps pass, and means for securing said back strap in various positions on the back portions of said straps, comprising fastening elements along the lengths of said first named straps at the back and cooperative with complementary fastening elements upon said horizontal back strap, said complementary fastening elements being mounted within said loops.

5. An undergarment having an upper part and a pendant skirt, the upper part comprising right and left sections each providing a coverage for a bust organ at the forward side of the body of the wearer and being connected together to prevent lateral separation of said sections at their front, the rear portions of the sections being disposed in overlapping engagement and stitched together for a minor fraction of their adjacent rear edges and providing a vertical gap at the back with freely separable upper edge portions and extending forwardly and connected to the opposite sections centrally of said bust coverage portion and crossing each other above said upper edge portions, and a cross strap having end loops slidably receiving said shoulder straps below the point of said crossing.
